UNITED STATES PATENT OFFICE.

LUCAS J. SMITH, OF EATON RAPIDS, MICHIGAN, ASSIGNOR OF ONE-HALF TO JOHN M. C. SMITH, OF CHARLOTTE, MICHIGAN.

EGG-CRATE-FILLER MACHINE.

No. 888,543.

Specification of Letters Patent.

Patented May 26, 1908.

Application filed April 3, 1907. Serial No. 366,193.

To all whom it may concern:

Be it known that I, LUCAS J. SMITH, a citizen of the United States, residing at the city of Eaton Rapids, county of Eaton, 5 State of Michigan, have invented certain new and useful Improvements in Egg-Crate-Filler Machines, of which the following is a specification.

This invention relates to an improved 10 machine for the manufacture of egg-crate fillers.

The objects of this invention are, first, to provide a simple and efficient machine which shall automatically produce the complete 15 egg-crate filler by simply feeding strips of strawboard thereto. Second, to provide in an egg-crate filler machine an improved means of guiding and supporting the tables or forms into which the cut and punched 20 cross strips are delivered. Third, to provide improved means of controlling the jaws of the gripping devices or holders carried by the said tables or forms. Fourth, to provide improved means of turning the tables or forms 25 as they progress through the machine. Fifth, to provide an improved feed for advancing the tables or forms step by step until they are filled with the strips for the 30 filler and then advancing the entire table or forms through a larger space. Sixth, to provide an improved means and construction for regulating the movements of the machine to prevent overthrow. Seventh, to provide improved means of regulating and controlling 35 the movements of a double punch whereby two strips of strawboard are perforated simultaneously. Eighth, to provide improved means of cutting off the punched strip and delivering it into the gripping jaws on the 40 table or forms.

Further objects, and objects relating to details of construction, will definitely appear from the detailed description to follow.

I accomplish the objects of my invention 45 by the devices and means described in the following specification.

The invention is clearly defined and pointed out in the claims.

A machine embodying the features of my 50 invention is fully illustrated in the accompanying drawing, forming a part of this specification, in which,

Figure 1 is a side elevation of the machine taken from the left-hand side of Fig. 2. Fig. 55 2 is a front elevation of the machine, showing

the side into which the paper or stock is delivered to be manufactured into egg-crate fillers. Fig. 3 is an enlarged detail sectional elevation, taken on a line corresponding to line 3—3 of Fig. 2, showing the cam mechanism for controlling the intermittent feed. Fig. 4 is an enlarged detail sectional elevation view taken on a line corresponding to line 4—4 of Fig. 1, showing the method of connecting the chains to the tables or forms and their guides and details, and the operation of the turning devices for the tables or forms as they are advanced through the machine. Fig. 5 is an enlarged detail sectional view on line 5—5 of Fig. 4, showing details of construction whereby the parts are adjusted and the finger 83 is located for opening the gripping jaws to receive the strips as they are cut off by the shear. Fig. 6 is an enlarged detail sectional view on line 6—6 of Fig. 4, 75 showing details of the devices for opening the jaws of the grippers on the tables or forms for receiving the strips forming the filler. Fig. 7 is an enlarged detail transverse sectional view on line 7—7 of Fig. 4, looking down, showing the relation of the guiding track whereby the turning of the cages is effected. Fig. 8 is an enlarged detail sectional elevation taken on a line corresponding to line 8—8 of Fig. 2, showing the feed mechanism, the die, cut-off knife, patty and patty cam in their relation to the tables or forms as they are advanced. Fig. 9 is a detail horizontal sectional view taken on a line corresponding to line 9—9 of Fig. 8, showing the 80 details of the patty. Fig. 10 is an enlarged detail sectional view taken on a line corresponding to line 10—10 of Fig. 8, showing the form of the punches. Fig. 11 is a sectional elevation view on line 11—11 of Fig. 8, 85 showing the method of securing the punch members in place. Fig. 12 is a detail plan view of a part of the feed table showing the method of adjustment of the guiding flanges to properly guide the strip of strawboard to 90 the machine. Fig. 13 is an enlarged sectional view on line 13—13 of Fig. 2, showing the details of construction of the paper feed ratchet. Fig. 14 is a detail longitudinal sectional view on line 14—14 of Fig. 13. Fig. 15 is an enlarged detail sectional view on line 15—15 of Fig. 2, showing the details of the 95 feed mechanism and ratchet for advancing the conveyer with its attached tables or forms from one table to the next. Fig. 16 is 100 105 110

a longitudinal sectional view on line 16—16 of Fig. 15. Fig. 17 is a view of the details of construction of the egg-crate filler when produced by my machine when it is completed.

5 In the drawing all of the sectional views are taken looking in the direction of the little arrows at the ends of the section lines, and similar numerals of reference refer to similar parts throughout the several views.

10 Referring to the numbered parts of the drawing, the main frame 1 is made up of two skeleton sides properly joined together, the frame being provided with legs for resting upon the floor or suitable foundation. This 15 frame consists of substantially a larger part having a pair of sprocket wheels at top and bottom upon which an endless carrier is arranged, the same consisting of a pair of sprocket chains 84, and on this carrier are 20 supported, at intervals, tables or forms carrying gripping jaws for receiving the cut and punched or slotted strips of strawboard or other material from which the egg-case fillers are formed. Adjacent to this carrier and the 25 forms or tables is supported a feeding, punching and shearing apparatus for cutting strips of strawboard or other material from the roll or sheet and delivering it to the gripping jaws on the tables or forms. With this general 30 description, I will proceed to describe first the feeding, punching and cutting portion of the machine, and thereafter in detail the carrier and the means of manipulating the tables or forms borne thereby and the means of controlling the jaws of the grippers on said 35 forms.

A counter-shaft 2, driven by the tight and loose pulleys 3, is arranged in the lower right-hand portion of the machine, as illustrated in 40 Fig. 1, a balance-wheel 4 being on the opposite end of the shaft from the pulleys 3. A spur gear 5 is borne by this counter-shaft and meshes with a gear 7, which is on the shaft 6, which is arranged parallel to the 45 shaft 2. Towards the opposite ends of the shaft 6 is a disk bearing wrist pin 8, which, through the pitman 9, actuates the feed rolls. There are two pairs of these feed rolls, each pair consisting of an upper roll 16—16 and a 50 lower roll 17—17, each roll being in sections. The lower rolls 17—17 are carried on shafts 10—10, and the upper rolls 16—16 are carried on shafts 15—15. On the left-hand end of the shafts 10—10, as illustrated in Fig. 2, 55 are supported ratchet wheels 13, secured to the said shafts by suitable set screws.

Journalized on the ends of the shafts 10—10 are disks 11, 11, one on each shaft, and each disk bears a pawl 14, which engages with the 60 teeth of the ratchet wheel 13, thereby giving to the shaft 10 and its rolls 17—17 an intermittent movement. The two disks 11 are coupled together by a link 12, so that they operate simultaneously in the same direction, and the pitman 9, before referred to,

extends from the wrist-pin 8 to the lower disk 11, and on each rotation of the shaft, it will be seen, operates the ratchet and advances the rolls 17, 17 one step. The parts are of such dimensions that this step advances the web of the strawboard 37, grasped between the rolls 16 and 17, the width of one of the cross-strips of the egg-case fillers. Towards each end of the shaft 6 are eccentrics and their straps 18—18, which are connected by suitable pitmen 19 to actuate the pairs of punches and shears which cut off the cross strips of the strawboard which go to make up the egg-case fillers.

The punch heads 20 are supported between suitable guides 22—22, there being two of these which are exactly similar. These heads are coupled together by the connecting rods or bars 21 at each side of the machine. The lower ends of each of these bars are provided with pivotal connections to which the pitmen 19 are coupled, so that, as the shaft 6 revolves, the eccentrics 18 referred to act through the connections just mentioned and the punches will be actuated by the heads 20 reciprocating up and down. Through the lower horizontal portion at the bottom of the heads 20 extend bolts 29, which secure individual punch plates 25 adjustably in position, so that the punches 26 can be readily adjusted in their proper relations to the die plate beneath, it being possible by this means to loosely put the several punches 26 in position, lower the punch head until each punch is inserted through the die plate 33 beneath, when they can be tightened by the set screws 29, and will, of course, accurately fit when the machine is put in operation.

The punches 26 are secured to their individual blocks 25 by being inserted into suitable sockets and retained there by spelter 28, a cross pin 27 preventing their withdrawal, as clearly appears in Fig. 11. The punch plate 33 has perforations corresponding to the punches 25 on the gang punch, the plate 33 being supported in a bed plate 31, this plate 31 being provided with the longitudinal strengthening ribs 32 on its under side. There is provided for the strawboard a guide plate 34, with apertures 36 therethrough, corresponding to the several punches, and it is secured a little above the bed plate 31 by means of screws 25 therethrough. See Fig. 8. Suitable washers are inserted between the plate 34 and the bed plate 31 to support the guide plate at the proper height.

On the back side of each punch head 20 is secured a suitable knife 30, the edge of which points downward and which co-operates with the knife 30' on the side of the bed plate 31, so that, on each reciprocation of the punch, the knives 30 will each of them cut off one of the cross strips which go to make up the egg-case fillers. Before the strip is cut off from the upper web it is projected into the grip-

ping jaws—which will be hereafter described—and from the lower web is partially forced into the slots cut in the cross strips of the egg-case fillers.

- 5 A patter plate 41 is below the knife 30' in each instance, and is reciprocated by suitable means to drive the cut-off strip well into the gripping jaws, or well into position in the cross-strips, as before referred to, the upper 10 patter plate 41 forcing the strip into the jaws and the lower patter plate driving the strip home in the slots on the cross strips which are slotted to receive the same. Each patter plate is supported on a pair of guide 15 members or pins 40'—40' towards each end, which pins reciprocate in suitable holes in the strengthening ribs 32 and the plate is actuated by a plunger or pin 40 near the center, also reciprocating in an aperture in the 20 ribs 32. On this plunger 40 is a collar 43, which is acted upon by coiled springs 42 for withdrawing the patter after it has been actuated. The front end of the plunger 40 is beveled at 44, and is acted upon by a cam- 25 wheel 45 on the shaft 10 between the sections of the feed rolls 17, so that, on each actuation of the feed rolls, and at the time the straw-board is being delivered to the punch, the patter is shoving home the strip that has 30 just been cut off.

The feed rolls 16—16 and 17—17 are supported in suitable stands 46, and are adjustable in their relation to each other by the hand screws 47 at each end, which are provided with suitable lock nuts 47'. Adjustable bearing plates 23 are provided on the guides 22 for securing the adjustment of the punch heads 20, the same being held in place by the bolts and lock nuts 24.

- 40 The paper is delivered to the feed rolls over the table 38, adjustable flanges 39 being held by suitable screws in slots therein to serve as guides for the edge of the strip 37 while it is being delivered to the feed rolls, 45 and by this means carried into the punch. These parts are exactly identical for each gang punch. The strawboard is taken from large rolls.

The strip of paper cut off by the upper 50 punch is indicated by the numeral 88 and the strip transverse thereto, which is cut off by the lower punch, is indicated by the numeral 90. These strips 88 and 90 are delivered to the tables or forms 77. These forms are provided with pairs of gripping jaws 80—81 arranged in seven rows across the face of the table or form 77. The upper jaw 81 being made of spring metal is riveted or otherwise secured in a fixed position on the face of the 55 plate. The lower jaw 80 extends through an aperture in the plate and the jaws of each row are secured to a rock shaft 78 whereby, when the rock shaft is operated, the jaws will be opened. This operation is clearly 60 indicated in Fig. 6, where the spring lever 82,

which controls the jaws by the rock shaft, is contacted with the pin 83, thereby depressing the jaws 80. A coiled spring is around each rock shaft 78, and puts tension upon the same to close the jaws 80 secured thereto 70 against the fixed or stationary jaws 81 after the pin 83 or other controlling stop or stops is passed.

A spindle or axle 73 is secured to the center of the plate 77 and extends through a suitable journal bearing in the cross bar 72. The cross bar 72 is guided at its opposite ends by the guides 76, which guides are arranged on the sides of the machine towards the punch heads to afford a substantial support for the 80 tables or forms while they are passing in front of the punches and are receiving the cut-off strips of strawboard. The details of the guides appear in Fig. 5, and their position is indicated by the dotted lines in Fig. 1, the 85 upper portion appearing in full lines in Fig. 2. Details of the relations of the cross bars on the cross heads 72 also appear in Fig. 8.

A collar 73' is on the spindle 73 to retain the cross arms 72 in position when they have 90 passed out from between the guides 76. On the inner end of the shaft 73 are arms 74 and 75, standing at right angles to each other at different points on the length of the shaft, and these arms are acted upon by the guides 95 85 and 86, respectively.

When the arm 74 is between the guides 85, the rows of gripping jaws on the tables or forms are in the horizontal position ready to receive the cut-off strips of strawboard from 100 the upper punch, and the jaws are forced open at this juncture by the pin 83, the positive relation of the parts clearly appearing in Fig. 4,—which acts upon the spring finger 82 secured to each shaft 79 for depressing 105 and opening the movable jaws 80. The position of the jaws is indicated in Fig. 6, and one set of the jaws slightly open also appears in Fig. 8, where the jaws have received the strip 88 that is just being cut off by the 110 knife 30. When the table is advancing the next step, the pin passes off from the finger 82 of the first rock shaft 78 and engages the next finger, opening that set of jaws and permitting the spring 79 on the first rock shaft 115 to close the jaws and securely grasp the cross strip of the filler that has just been delivered to it. As the table or form advances downward, the arm 74 passes out from between the guides 85, leaving the table or form free 120 to rotate in the journal bearing in the cross strip 72, except that the arm 75 at right angles thereto will strike the guides 86 and, as the cross arm 72 advances, the arm 75 strikes against the guides 86 and is embraced 125 thereby, and the table or form 77 is turned one quarter around, or at right angles to its first position. It then descends step by step in front of the lower punch and shear, which delivers the transverse strips 92 and 130

forces them in the slots cut in the strips 88 by the punches, and the patter, exactly similar to the one illustrated in Figs. 8 and 9, then drives the strip home until seven strips 5 have been inserted in the corresponding notches in the strips 88. The notches punched out in the strip 88 have a jog or tooth 89 therein, which correspond to a triangular aperture 92 in the strips 90, and both 10 slots are broad at their outer ends to serve as guides for the cross strips that are delivered thereto or received thereby.

The pair of sprocket chains 84 is carried by oppositely arranged pairs of sprocket 15 wheels 65. The sprocket wheels are carried on shafts 48 and 66. The upper shaft 66 is in an adjustable bearing whereby the sprocket chains can be put under suitable tension. When the chains become worn, 20 so that the tables or forms are too much separated, I remove a link of each chain between each pair of tables or forms and substitute a slightly shorter link. This is the means which I have adopted for overcoming 25 the defects occasioned by the wear of the chains. The boxing for the shaft is adjustable by the screw 68 operated by a suitable hand wheel, clearly illustrated in Fig. 1. I apply a brake band 70 to a suitable hub 69 30 on the upper sprocket wheel 76. The brake band is adjustable by the thumb screw 71, clearly appearing in Fig. 2. By this means, the parts are always actuated under friction, so that overthrow is thereby largely avoided. 35 The spring fingers 82 which control the different pairs of the jaws as they pass up on the back side of the machine encounter the elongated stop 87, which contacts with all of the fingers of any one plate or form opening 40 all of the jaws, thereby releasing the completed egg-case filler, which can be picked off by an operator at that point. The jaws might be operated in the lower position and the filler released and allowed to drop of its own 45 weight, but this is not of any especial advantage, as the fillers need to be handled for the purpose of packing anyway.

The step by step feed of the carrier and tables is accomplished by means of a pair of 50 ratchet wheels, the one on the left-hand side of Fig. 2 securing the regular step by step movement, and the one on the right-hand side securing the double step necessary for carrying the tables or forms forward and 55 bringing a new table or form into place, the extra space being made necessary by the requirement of separating the plates, so that they can rotate independently without interfering with each other, it being observed 60 that such space is necessary by an inspection of Figs. 1 and 8.

The ratchet mechanism on the left-hand end of the shaft 48 consists of the ratchet wheel 62 which is secured by suitable means 65 to the shaft 48. A disk 49 rotates on the shaft

48 and carries a ratchet pawl 63, which is arranged to act upon the teeth of the ratchet wheel, 62. This disk is actuated by the pitman 51, which is operated by the eccentric 50 on the shaft 6, so that, on each rotation of the shaft 6, the eccentric 50, through the pitman 51, advances the carrier one step which advances the table a distance equal to the space between the cross strips of the filler. When seven strips of the filler 70 have been thus inserted, it is necessary that the table or form be advanced two steps in order that the first pair of jaws of the next table be brought into the right position to receive the strip that is cut off, or the table 80 or form in the lower position be advanced far enough to receive the first cut-off strip in the slots of the strips that have just passed to position. This is accomplished by means of the ratchet wheel 60 fixed on 85 the opposite end of the shaft 48, which has teeth or notches spaced nine times as far apart as the notch on the wheel 62.

A disk 59 is provided which is operated by a pitman 58 bearing a pawl 61, which has 90 a stroke double the stroke of the pawl 63. The space between the teeth on the disk 60 is smooth. The pitman 58 is actuated by a cam mechanism, a cam 55 being secured towards the right-hand end of the shaft 6, 95 as illustrated in Fig. 2. The cam acts upon a roller 54, which is in an adjustable block 53 and reacts upon a lever 52, which is fulcrumed at 56 and acts through its connections on the pitman 58, above referred to, so that, on each revolution of the shaft 6, the pawl 61 is reciprocated twice the distance of the pawl 63, but the teeth on the ratchet wheel 60 are so far apart that it is necessary that this wheel be revolved seven 100 steps through its connections with the shaft 48, which is actuated by the pawl 63, before the pawl 61 engages the notches of the ratchet wheel, and, when it engages said notch, as it operates double the distance of 105 the pawl 63, it will advance the shaft 48 and the carrier and other parts twice that distance, thus securing the irregular movement of the carriage that is desirable in advancing the same properly through the 110 machine after each plate is filled.

I desire to remark that the cam 55 is very desirable for this purpose, because it completely regulates the movement for advancing the ratchet. However, an eccentric is 120 used for the purpose of advancing the shorter distances, because the momentum of the parts is not here so great, and I have therefore shown an eccentric on one end of the shaft and a cam mechanism on the opposite 125 end, thereby showing mechanism which could be interchangeable for this purpose. The eccentric would require a lower speed.

I have now described all of the parts of my improved machine for manufacturing egg- 130

crate fillers. I will now indicate briefly the operation of the machine and the actuation of the various parts. The strawboard from which these egg-crate fillers are usually made is fed from suitable rolls, the strip 37 being guided over the table 38 by guides 39—39 at each side. Each strip is delivered between two pairs of rollers 16—17, which are advanced intermittently and step by step by 10 the ratchet wheel 13, acted upon by the ratchet pawl 14, the two being coupled together by the pitman 12. As the material is advanced under the guide plates 34, the punch heads 20, with the punches thereon, 15 are forced downward by their connection with the eccentrics 18, and apertures, corresponding to the slots in the filler, are punched through the strips 37. The punches are made to correspond to the apertures desired 20 to be punched. At the next rotation of the shaft 6, each strip of strawboard is advanced a second step. Another set of holes is then punched in each and also the shears 30 descend and cut off the end of each roll of straw- 25 board, which has been delivered forwardly, the upper one between a pair of jaws 80—81. On the next stroke of the machine, the operations just referred to are repeated, the punch 30 punching out a new strip, the shear cutting off another strip, and the mechanism by the eccentric 50 and its connection 51 to the ratchet disk 49, carrying the pawl 63 acts upon the ratchet disks 62 and advances the carriage one step. The spring finger 82, 35 which contacted with the actuating pin 83, is moved out of contact and the jaw 80 is allowed to close and grasp the cut-off piece 88. The first strip cut off descends now opposite the patter plates 41 and is driven home to 40 the bottom of the jaws 80—81. When this operation has been repeated seven times, the pawl on the right-hand side of the machine, as illustrated in Fig. 2, comes into play and advances the carrier with the tables or forms 45 a double step, and the upper is released from the guides 85, the same being turned a quarter around by the finger 85, and passed into the guides 86. The finger 74 passes out of the guides 85, and the plate or table that has 50 just received the cross strips of the fillers, passes out of the guide 86 and is turned back by the finger 74 again passing into the guides 85, which guides extend entirely around the machine, as clearly appears by an inspection 55 of their relation to Fig. 1, the guides curving around the axes of rotation of the sprocket wheels at top and bottom and then continuously up on the back of the machine.

The lower punch and shear are substantially identical in their structure and operation with the upper, except that the punch punches the transverse strip 90, which is the complement of the strip 88, and is notched to embrace the same, and the notches in the strip 88 embrace the transverse strip 90, and

the transverse strip 90, in place of being delivered to the jaws of the machine, is delivered into the slots 89 of the strip 88, the slot 91 embracing the strip 88 and the parts being locked together by a point engaging the perforations 92. The relation of these parts clearly appears in Fig. 17, where they are shown assembled. As the machine continues to operate, the spring fingers 82 pass up into contact with the stop bar 87 at the back of the machine and all the jaws 80—81 on each plate or table are opened, and the operator picks the egg-case fillers off from the tables or forms, folds them together and packs them away ready for shipment or subsequent use.

I have thus described my improved egg-case filler in all of its details, and I believe the details are in the form best adapted for use in this relation. I believe the special features which I have illustrated in each instance co-act specially with the other parts and portions of the machine and I, therefore, desire to state that I claim the different specific features and that I also desire to claim the features broadly in their relations to the machine, for, while I am aware that continuous carriers have been heretofore used on which tables or forms have been pivotally mounted, containing certain devices for receiving and handling the cross strips of an egg-case filled, and, while such strips have been punched and delivered to the machine, I believe that the means which I have produced and combined are especially well adapted to the ends intended in that they provide fully for controlling all of the parts of the machine, and that the result is accomplished with a minimum amount of mechanism and material. I believe that many of the special features I have shown might be employed to advantage in other styles of egg-case filler machines, and I shall desire to claim such features in whatever relation they may be found. I believe, however, that the various parts I have shown co-operate very effectively together in the machine I have here produced.

Having thus described my invention, what I claim as new and desire to secure by Letters Patent is:

1. In an egg crate filler machine, the combination of a suitable frame 1; a pair of punch-heads 20—20 arranged one above the other carrying gangs of punches 26 adjustable thereon; die plates 34 corresponding thereto, supported in suitable bases; a driven shaft 6 in the machine; eccentrics on said shaft with connecting rods or pitmen connected to the said punch-heads to actuate the same simultaneously; shears 30 secured to said punch-heads for cutting off the punched strips; a patter plate 41 below each of said shears; reciprocating pins for supporting the same; feed rolls 16—17, 16—17, 125

for delivering the strips of strawboard to the punch and shears; a cam wheel on the lower feed roll shaft of each pair to actuate the corresponding patter; suitable guides for 5 guiding the said strips to said feed rolls; ratchet mechanismrs; suitable disks 11 and 11 on the feed roll shafts for carrying said ratchet mechanisms; a rod 12, for coupling said disks for actuating the said feed rolls by 10 a step-by-step movement; a pitman 9; a disk on the end of the shaft 6 having a wrist-pin 8 to which said pitman is coupled, for actuating the ratchets of the feed rolls; an endless carrier 84, consisting of a pair of sprocket 15 chains oppositely-arranged sprocket-wheels 65 and 65 within the said frame-work to support said carrier; a lower shaft 48 and an upper shaft 66 to support said sprocket wheels; adjustable journal bearings for said 20 upper shaft 66 to put tension on the said carrier; suitable cross-arms 72 at intervals on the said carrier; guides 76 for the ends of said cross-arms at each side of said punches to keep them in their proper relation 25 to the said punching machines; plates or forms 77; suitable rock shafts 73, for carrying said plates or forms one of which is journaled in each of said cross-bars 72; rows of oppositely-faced jaws 80—81 on the face of each 30 of said plates, one set of jaws 81 being fixed and the other set of jaws 80 being movable; a rock shaft 78 to which the said movable jaws 80 are secured; a spring 79 to hold the said jaws normally closed; a spring finger 82 35 on each of said rock shafts; trip fingers 83 for acting upon the said spring finger 82 to open the jaws; a trip bar 87 toward the rear of the machine for opening all of the jaws on each plate or table in passing; fingers 74—75 40 at right angles to each other on the inner end of rock shaft 73, at different points on the length thereof; guides 85 extending from near the bottom around the frame parallel to the path of the carrier, past the upper 45 punch and positioned to engage the fingers 74 of each of said plates or forms as it passes; guides 86 positioned within the guide 85 and between the opposite ends thereof to embrace the finger 75 to turn the table or form at 50 right angles to its initial position, as it passes the lower punch and cutter and permit the same to be released and swung back to the initial position as it passes from said guides; a brake mechanism for retarding the 55 movement of said endless carrier; a feed mechanism for the carrier consisting of the ratchet wheels and pawls on opposite ends of the shaft 48; an eccentric 50 on the shaft 48 with connections 51 for actuating one of 60 the said ratchets to secure the shorter steps; a cam 55 toward the opposite end of said shaft 48 with connections for actuating the pawl of the opposite ratchet a double stroke, the notches of the ratchet on the double 65 stroke pawl being separated so that the same

operates only at widely separated intervals, as the shaft is rotated or driven by the shorter strokes of the first-named ratchet, all co-acting for the purpose specified.

2. In an egg crate filler machine, the combination of a suitable frame 1; a pair of punch-heads 20—20 arranged one above the other carrying gangs of punches 26; die plates 34 corresponding thereto, supported in suitable bases; means for actuating said punch-heads simultaneously; shears carried by the said punch-head for cutting off the punched strips; means for delivering the same into suitable supports; an endless carrier 84, consisting of a pair of sprocket chains 80 oppositely-arranged sprocket-wheels 65 and 65 within the said frame-work to support said carrier; a lower shaft 48 and an upper shaft 66 to support said sprocket wheels; adjustable journal bearings for said upper 85 shaft 66 to put tension on the said carrier; suitable cross-arms 72 at intervals on the said carrier 84; guides 76 for the ends of said cross-arm at each side of said punches to keep them in their proper relation to the 90 said punching machine; plates or forms 77; suitable rock shafts 73 for carrying said plates or forms one of which is journaled in each of said cross-bars 72; rows of oppositely-faced jaws 80—81 on the face of each 95 of said plates, one set of jaws 81 being fixed and the other set of jaws 80 being movable; a rock shaft 78 to which the said movable jaws 80 are secured; a spring 79 to hold the said jaws normally closed; a spring finger 82 100 on each of said rock shafts; trip fingers 83 for acting upon the said spring finger 82 to open the jaws; a trip bar 87 toward the rear of the machine for opening all of the jaws on each plate or table in passing; fingers 74—75 105 at right angles to each other on the inner end of the rock shaft 73, at different points on the length thereof; guides 85 extending from near the bottom around the frame parallel to the path of the carrier, past the upper 110 punch and positioned to engage the fingers 74 of each of said plates or forms as it passes; guides 86 positioned within the guide 85 and between the opposite ends thereof to embrace the finger 75 to turn the table or form 115 at right angles to its initial position as it passes the lower punch and cutter and permit the same to be released and swing back to the initial position as it passes from said guides; a brake mechanism for retarding the 120 movement of said endless carrier; a feed mechanism for the carrier consisting of the ratchet wheels and pawls on opposite ends of the shaft 48; an eccentric 50 on the shaft 48 with connections 51 for actuating one of 125 the said ratchets to secure the shorter steps; a cam 55 toward the opposite end of said shaft 48, with connections for actuating the pawl of the opposite ratchet a double stroke, the notches of the ratchet on the double 130

stroke pawl being separated so that the same operates only at widely separated intervals, as the shaft is rotated or driven by the shorter strokes of the first-named ratchet, 5 all coacting for the purpose specified.

3. In an egg crate filler machine, the combination of a suitable frame 1; a pair of punch-heads 20—20 arranged one above the other carrying a gang of punches 26 adjustable thereon; die plates 34 corresponding thereto, supported in suitable bases; a driven shaft 6 in the machine; eccentrics on said shaft with connecting rods or pitmen connected to the said punch-heads to actuate the 10 same simultaneously; shears 30 secured to said punch-heads for cutting off the punched strips; a patter plate 41 below each of said shears; reciprocating pins for supporting the same; feed rolls 16—17, 16—17 for delivering the strips of strawboard to the punch and shears; a cam wheel on the lower feed roll shaft of each pair to actuate the corresponding patter; suitable guides for guiding the said strips to said feed rolls; ratchet 15 mechanisms; suitable disks 11 and 11, on the feed roll shafts for carrying said ratchet mechanisms; a rod 12 for coupling said disks for actuating the said feed rolls by a step-by-step movement; a pitman 9; a disk on the 20 end of the shaft 6 having a wrist-pin 8 to which said pitman is coupled for actuating the ratchets of the feed rolls; an endless carrier 84, consisting of a pair of sprocket chains oppositely-arranged sprocket-wheels 65 and 35 65 within the said frame-work to support said carrier; a lower shaft 48 and an upper shaft 66 to support said sprocket wheels; adjustable journal bearings for said upper shaft 66 to put tension on the said carrier; suitable 40 cross-arms 72 at intervals on the said carrier 84; guides 76 for the ends of said cross-arms at each side of said punches to keep them in their proper relation to the said punching machines; plates or forms 77; suitable rock 45 shafts 73 for carrying said plates or forms; one of which is journaled in each of said cross-bars 72; rows of oppositely-faced jaws 80—81 on the face of each of said plates, one set of jaws 81 being fixed and the other set of jaws 50 80 being movable; a rock shaft 78 to which the said movable jaws 80 are secured; a spring 79 to hold the said jaws normally closed; a spring finger 82 on each of said rock shafts; trip fingers 83 for acting upon 55 the said spring finger 82 to open the jaws; a trip bar 87 toward the rear of the machine for opening all of the jaws on each plate or table in passing; fingers 74—75 at right angles to each other on the inner end of the rock shaft 73, at different points on the length thereof; guides 85 extending from near the bottom around the frame parallel to the path of the carrier, past the upper punch and positioned to engage the fingers 74 of each of said 60 plates or forms as it passes; guides 86 positioned within the guide 85 and between the 65

tioned within the guide 85 and between the opposite ends thereof to embrace the fingers 75 to turn the table or form at right angles to its initial position as it passes the lower punch and cutter and permit the same to be released and swung back to the initial position as it passes from said guides; a feed mechanism for the carrier consisting of the ratchet wheels and pawls on opposite ends of the shaft 48; an eccentric 50 on the shaft 48 with connections 51 for actuating one of the said ratchets to secure the shorter steps, and a cam 55 toward the opposite end of said shaft 48, with connections for actuating the pawl of the opposite ratchet a double stroke, 70 the notches of the ratchet on the double stroke pawl being separated so that the same operates only at widely separated intervals, as the shaft is rotated or driven by the shorter strokes of the first-named ratchet, all 75 coacting for the purpose specified.

4. In an egg crate filler, the combination of a suitable frame 1; a pair of punch-heads 20—20 arranged one above the other carrying gangs of punches 26; a die plate 34 corresponding thereto, supported in suitable bases; means for actuating said punch-heads simultaneously; shears carried by the said punch-head for cutting off the punched strips; means for delivering the same into 90 suitable supports; an endless carrier 84 consisting of a pair of sprocket chains oppositely-arranged sprocket wheels 65 and 65 within the said frame-work to support said carrier; a lower shaft 48 and an upper shaft 100 66 to support said sprocket wheels; adjustable journal bearings for said upper shaft 66 to put tension on the said carrier; suitable cross-arms 72 at intervals on the said carrier 84; guides 76 for the ends of said cross-arms 105 at each side of said punches to keep them in their proper relation to the said punching machines; tables or forms 77; suitable rock shafts 73 for carrying said plates or forms; one of which is journaled in each of said cross-bars 72; rows of oppositely-faced jaws 80—81 on the face of each of said plates, one set of jaws 81 being fixed and the other set of jaws 80 being movable; a rock shaft 78 to which the said movable jaws 80 are secured; a spring 79 to hold the said jaws normally closed; a spring finger 82 on each of said rock shafts; trip fingers 83 for acting upon the said spring finger 82 to open the jaws; a trip bar 87 toward the rear of the machine 110 for opening all of the jaws on each plate or table in passing; fingers 74—75 at right angles to each other on the inner end of the rock shaft 73, at different points on the length thereof; guides 85 extending from near the bottom around the frame parallel to the path of the carrier, past the upper punch and positioned to engage the fingers 74 of each of said plates or forms as it passes; guides 86 positioned within the guide 85 and between the 115 120 125 130

opposite ends thereof to embrace the fingers 75 to turn the table or form at right angles to its initial position as it passes the lower punch and cutter and permit the same to be released and swung back to the initial position as it passes from said guides; a feed mechanism for the carrier consisting of the ratchet wheels and pawls on opposite ends of the shaft 48, an eccentric 50 on the shaft 48 with connections 51 for actuating one of the said ratchets to secure the shorter steps, and a cam toward the opposite end of said shaft 48, with connections for actuating the pawl of the opposite ratchet a double stroke, the notches of 10 the ratchet on the double stroke pawl being separated so that the same operates only at widely separated intervals, as the shaft is rotated or driven by the shorter strokes of the first-named ratchet, all coacting for the 20 purpose specified.

5. In an egg crate filler, the combination of a suitable frame 1; a pair of punch-heads 20—20 arranged one above the other carrying gangs of punches 26 adjustable thereon; 25 die plates 34 corresponding thereto, supported in suitable bases; a driven shaft 6 in the machine; eccentrics on said shaft with connecting rods or pitmen connected to the said punch-heads to actuate the same simultaneously; shears 30 secured to said punch-heads for cutting off the punched strips; a patter plate below each of said shears; reciprocating pins for supporting the same; feed rolls 16—17, 16—17 for delivering the strips 30 of strawboard to the punch and shears; a cam wheel on the lower feed roll shaft of each pair to actuate the corresponding patter; suitable guides for guiding the said strips to said feed rolls; ratchet mechanism; suitable 40 disks 11 and 11 on the feed roll shafts for carrying said ratchet mechanism; a rod 12 for coupling said disks for actuating the said feed rolls by a step-by-step movement; a pitman 9; a disk on the end of the shaft 6 45 having a wrist-pin 8 to which said pitman is coupled for actuating the ratchets of the feed rolls; an endless carrier 84, consisting of a pair of sprocket chains oppositely-arranged sprocket-wheels 65 and 65 within the said 50 frame-work to support said carrier; a lower shaft 48 and an upper shaft 66 to support said sprocket wheels; adjustable journal bearings for said upper shaft 66 to put tension on the said carrier; suitable cross-arms 55 72 at intervals on the said carrier 84; guides 76 for the ends of said cross-arms at each side of said punches to keep them in their proper relation to the said punching machine; plates or forms 77; suitable rock 60 shafts 73 for carrying said plates or forms; one of which is journaled in each of said cross-bars 72; the said forms being of such dimension as to swing without interfering with each other; rows of oppositely-faced 65 jaws 80—81 on the face of each of said plates,

one set of jaws 81 being fixed and the other set of jaws 80 being movable; a rock shaft 78 to which the said movable jaws 80 are secured; a spring 79 to hold the said jaws normally closed; a spring finger 82 on each 70 of said rock shafts; trip fingers 83 for acting upon the said spring finger 82 to open the jaws; a trip bar 87 toward the rear of the machine for opening all of the jaws on each plate or table in passing; fingers 74—75 at right 75 angles to each other on the inner end of the rock shaft 73, at different points on the length thereof; guides 85 extending from near the bottom around the frame parallel to the path of the carrier, past the upper 80 punch and positioned to engage the fingers 74 of each of said plates or forms as it passes; guides 86 positioned within the guide 85 and between the opposite ends thereof to embrace the finger 75 to turn the table or form 85 at right angles to its initial position as it passes the lower punch and cutter and permit the same to be released and swung back to the initial position as it passes from said guides; a brake mechanism for retarding the 90 movement of said endless carrier; suitable feed mechanism for advancing the carrier step by step as each plate is passing the punch-heads; and a mechanism for advancing the carrier an increased distance sufficient 95 to carry the next succeeding plate on the carrier into operative relation with the punch mechanism; and to compensate for the difference in distances between the successive plates and between the successive rows of 100 grippers on the same plate, all coacting for the purpose specified.

6. In an egg crate filler machine, the combination of the main frame 1; a pair of punch-heads 20—20 arranged one above the other, carrying gangs of punches; die plates 34 corresponding thereto, supported in suitable bases; means for actuating said punch-heads simultaneously; shears carried by the said punch-head for cutting off the punched 110 strips; means for delivering the same into suitable supports; an endless carrier 84, consisting of a pair of sprocket chains; oppositely-arranged sprocket-wheels 65 and 66 within the said frame-work to support said carrier; 115 a lower shaft 48 and an upper shaft 66 to support said sprocket-wheels; adjustable journal bearings for said upper shaft 66 to put tension on the said carrier; suitable cross-arms 72 at intervals on the said carrier 84; guides 76 for the ends of said cross-arms at each side of said punches to keep them in their proper relation to the said punching machine; plates or forms 77; suitable rock 120 shafts 73 for carrying said plates or forms; one of which is journaled in each of said cross-bars 72; the said forms being of such dimension as to swing without interfering with each other; rows of oppositely-faced 125 jaws 80—81 on the face of each of said plates, 130

one set of jaws 81 being fixed and the other set of jaws 80 being movable; a rock shaft 78 to which the said movable jaws 80 are secured; a spring 79 to hold the said jaws 80 normally closed; a spring finger 82 on each of said rock shafts; trip fingers 83 for acting upon the said spring finger 82 to open the jaws; a trip bar 87 toward the rear of the machine for opening all of the jaws on each 5 plate or table in passing; fingers 74—75 at right angles to each other on the inner end of the rock shaft 73, at different points on the length thereof; guides 85 extending from near the bottom around the frame parallel to 10 the path of the carrier, past the upper punch and positioned to engage the fingers 74 of each of said plates or forms as it passes; guides 86 positioned within the guide 85 and between the opposite ends thereof to embrace 15 the finger 75 to turn the table or form at right angles to its initial position as it passes the lower punch and cutter and permit the same to be released and swung back to the initial position as it passes from said guides; 20 a brake mechanism for retarding the movement of said endless carrier; suitable feed mechanism for advancing the carrier step by step as each plate is passing the punch-heads; and a mechanism for advancing the 25 carrier an increased distance sufficient to carry the next succeeding plate on the carrier into operative relation with the punch mechanism and to compensate for the difference in the distances between the successive 30 plates and between the successive rows of grippers on the same plate; all coacting for the purpose specified.

7. In an egg crate filler machine, the combination of a suitable frame 1; a pair of 35 punch-heads 20—20 arranged one above the other carrying gangs of punches 26 adjustable thereon; die plates 34 corresponding thereto, supported in suitable bases; a driven shaft 6 in the machine; eccentrics on 40 said shaft with connecting rods or pitmen connected to the said punch-heads to actuate the same simultaneously; shears 30 secured to said punch-heads for cutting off the punched strips; a patter plate 41 below each of said 45 shears; reciprocating pins for supporting the same; feed rolls 16—17, 16—17 for delivering the strips of strawboard to the punch and shears; a cam wheel on the lower feed roll shaft of each pair to actuate the corresponding patter; suitable guides for guiding the 50 said strips to said feed rolls; ratchet mechanisms; suitable disks 11 and 11, on the feed roll shafts for carrying said ratchet mechanisms; a rod 12 for coupling said disks for 55 actuating the said feed rolls by a suitable step-by-step movement; a pitman 9; a disk on the end of the shaft 6 having a wrist pin 8 to which said pitman is coupled, for actuating the ratchets of the feed rolls; an endless 60 carrier 84 consisting of a pair of sprocket chains; oppositely-arranged sprocket-wheels 65 and 65 within the said frame-work to support 65 the carrier; a lower shaft 48 and an upper shaft 66 to support said sprocket-wheels; adjustable journal bearings for said 70 upper shaft 66 to put tension on the said carrier; suitable cross-arms 72 at intervals on the said carrier; guides 76 for the ends of said cross-arms at each side of said punches to keep them in their proper relation to the 75 said punching machines; plates or forms 77; suitable rock shafts 73 for carrying said plates or forms one of which is journaled in each of said cross-bars 72; the said forms being of such dimension as to swing without 80 interfering with each other; rows of oppositely-faced jaws 80—81 on the face of each of said plates, one set of jaws 81 being fixed and the other set of jaws 80 being movable; a rock shaft 78 to which the said movable 85 jaws 80 are secured; a spring 79 to hold the said jaws normally closed; a spring finger 82 on each of said rock shafts; trip fingers 83 for acting upon the said spring finger 82 to open the jaws; a trip bar 87 toward the rear 90 of the machine for opening all of the jaws on each plate or table in passing; fingers 74—75 at right angles to each other on the inner end of the rock shaft 73, at different points on the length thereof; guides 85 extending from 95 near the bottom around the frame parallel to the path of the carrier, past the upper punch and positioned to engage the fingers 74 of each of said plates or forms as it passes; guides 86 positioned within the guide 85 and between the opposite ends thereof to embrace the finger 75 to turn the table or form at right angles to its initial position as it passes the lower punch and cutter and permit the same to be released and swung back 100 to the initial position as it passes from said guides; suitable feed mechanism for advancing the carrier step by step as each plate is passing the punch-heads; and a mechanism for advancing the carrier an increased distance sufficient to carry the next succeeding plate on the carrier into operative relation with the punch mechanism and to compensate for the difference in the distances between the successive plates and between the 105 successive rows of grippers on the same plate; all coacting for the purpose specified.

8. In an egg crate filler machine, the combination of a suitable frame 1; a pair of punch-heads 20—20 arranged one above the other carrying gangs of punches 26; die plates 34 corresponding thereto, supported in suitable bases; means for actuating said punch heads simultaneously; shears carried by the said punch head for cutting off the 110 punched strips; means for delivering the same into suitable supports; an endless carrier 84, consisting of a pair of sprocket chains; oppositely arranged sprocket-wheels 65 and 65 within the said frame-work to support 115

said carrier; a lower shaft 48 and an upper shaft 66 to support said sprocket-wheels; adjustable journal bearings for said upper shaft 66 to put tension on said carrier; suitable 5 cross-arms 72 at intervals on the said carrier 84; guides 76 for the ends of said cross-arms at each side of said punches to keep them in their proper relation to the said punching machines; plates or forms 77; suitable rock 10 shafts 73 for carrying said plates or forms one of which is journaled in each of said cross-bars 72; the said forms being of such dimension as to swing without interfering with each other; rows of oppositely-faced 15 jaws 80—81 on the face of each of said plates, one set of jaws 81 being fixed and the other set of jaws 80 being movable; a rock shaft 78 to which the said movable jaws 80 are secured; a spring 79 to hold the said jaws normally closed; a spring finger 82 on each of 20 said rock shafts; trip fingers 83 for acting upon the said spring finger 82 to open the jaws; a trip bar 87 toward the rear of the machine for opening all of the jaws on each 25 plate or table in passing; fingers 74—75 at right angles to each other on the inner end of the rock shaft 73, at different points on the length thereof; guides 85 extending from near the bottom around the frame parallel to 30 the path of the carrier, past the upper punch and positioned to engage the fingers 74 of each of said plates or forms as it passes; guides 86 positioned within the guide 85 and between the opposite ends thereof to embrace 35 the finger 75 to turn the table or form at right angles to its initial position as it passes the lower punch and cutter and permit the same to be released and swung back to the initial position as it passes from said guides; 40 suitable feed mechanism for advancing the carrier step by step as each plate is passing the punch-heads; and a mechanism for advancing the carrier an increased distance sufficient to carry the next succeeding plate 45 on the carrier into operative relation with the punch mechanism and to compensate for the difference in the distances between the successive plates and between the successive rows of grippers on the same plate; all coacting 50 for the purpose specified.

9. In an egg-crate filler machine, the combination of a suitable frame 1; a pair of punch-heads 20—20 arranged one above the other carrying gangs of punches 26 adjustable thereon; die plates 34 corresponding thereto, supported in suitable bases; a driven shaft 6 in the machine; eccentrics on said shaft with connecting rods or pitmen connected to the said punch-heads to actuate the 60 same simultaneously; shears 30 secured to said punch-heads for cutting off the punched strips; a patter plate 41 below each of said shears; reciprocating pins for supporting the same; feed rolls 16—17, 16—17, for delivering the strips of strawboard to the punch and 65 shears; a cam wheel on the lower feed roll shaft of each pair to actuate the corresponding patter; suitable guides for guiding the said strips to said feed rolls; ratchet mechanisms; suitable disks 11 and 11 on the feed roll shafts, for carrying said ratchet mechanisms; a rod 12 for coupling said disks, for actuating the said feed rolls by a step-by-step movement; a pitman 9; a disk on the end of the shaft 6 having a wrist-pin 8 to 70 which said pitman is coupled, for actuating the ratchets of the feed rolls; an endless carrier 84, consisting of a pair of sprocket chains oppositely-arranged sprocket-wheels 65 and 65 within the said frame-work to support 75 said carrier; a lower shaft 48 and an upper shaft 66 to support said sprocket-wheels; adjustable journal bearings for said upper shaft 66 to put tension on the said carrier; suitable cross-arms 72 at intervals on the said carrier 80 84; guides 76 for the ends of said cross-arms at each side of said punches to keep them in their proper relation to the said punching machines; plates or forms 77; suitable rock shafts 73 for carrying said plates or forms 90 one of which is journaled in each of said cross-bars 72; rows of oppositely-faced jaws on the face of each of said plates, the jaws being movable in relation to each other; means for opening the jaws to receive the cut off 95 strips as the plates are passing the first punch head; means for opening each of the jaws on a plate after the same have passed both punch-heads to permit the withdrawing of the completed egg case filler; fingers 74—75 100 at right angles to each other on the inner end of the rock shaft 73, at different points on the length thereof; guides 85 extending from near the bottom around the frame parallel to the path of the carrier, past the upper punch 105 and positioned to engage the fingers 74 of each of said plates or forms as it passes; guides 86 positioned within the guide 85 and between the opposite ends thereof to embrace the finger 75 to turn the table or form 110 at right angles to its initial position as it passes the lower punch and cutter and permit the same to be released and swung back to the initial position as it passes from said guides; a brake mechanism for retarding the 115 movement of said endless carrier; a feed mechanism for the carrier consisting of the ratchet wheels and pawls on opposite ends of the shaft 48; an eccentric 50 on the shaft 48 with connections 51 for actuating one of the 120 said ratchets to secure the shorter steps, and a cam 55 toward the opposite end of said shaft 48, with connections for actuating the pawl of the opposite ratchet a double stroke, the notches of the ratchet on the double 125 stroke pawl being separated so that the same operates only at widely separated intervals, as the shaft is rotated or driven by the shorter strokes of the first-named ratchet, all coacting for the purpose specified. 130

10. In an egg crate filler machine, the combination of a suitable frame 1; a pair of punch-heads 20—20 arranged one above the other carrying gangs of punches 26 adjustable thereon; die plates 34 corresponding thereto, supported in suitable bases; means for actuating said punch-heads simultaneously; shears carried by the said punch-heads for cutting off the punched strips; 10 means for delivering the same into suitable supports; an endless carrier 84, consisting of a pair of sprocket chains oppositely - arranged sprocket - wheels 65 and 65 within the said frame-work to support said carrier; 15 a lower shaft 48 and an upper shaft 66 to support said sprocket-wheels; adjustable journal bearings for said upper shaft 66 to put tension on the said carrier; suitable cross-arms 72 at intervals on the said carrier 84; 20 guides 76 for the ends of said cross-arms at each side of said punches to keep them in their proper relation to the said punching machine; plates or forms 77; suitable rock shafts 73 for carrying said plates or forms 25 one of which is journaled in each of said cross-bars 72; rows of oppositely-faced jaws on the face of each of said plates, the jaws being movable in relation to each other; means for opening the jaws to receive the cut 30 off strips as the plates are passing the first punch-head; means for opening each of the jaws on a plate after the same have passed both punch-heads, to permit the withdrawal of the completed egg case filler; fingers 35 74—75 at right angles to each other on the inner end of the rock shaft 73, at different points on the length thereof; guides 85 extending from near the bottom around the frame parallel to the path of the carrier, past 40 the upper punch and positioned to engage the fingers 74 of each of said plates or forms as it passes; guides 86 positioned within the guide 85 and between the opposite ends thereof to embrace the finger 75 to turn the 45 table or form at right angles to its initial position as it passes the lower punch and cutter and permit the same to be released and swung back to the initial position as it passes from said guides; a brake mechanism for retarding the movement of said endless carrier; 50 a feed mechanism for the carrier consisting of the ratchet wheels and pawls on opposite ends of the shaft 48, an eccentric 50 on the shaft 48 with connections 51 for actuating one of the said ratchets to secure the shorter steps, and a cam 55 towards the opposite end of said shaft 48 with connections for actuating the pawl of the opposite ratchet a double stroke, the notches of the ratchet 55 on the double stroke pawl being separated so that the same operates only at widely separated intervals, as the shaft is rotated or driven by the shorter strokes of the first-named ratchet, all coacting for the purpose 60 specified.
11. In an egg crate filler machine, the combination of a suitable frame 1; a pair of punch-heads 20—20 arranged one above the other carrying gangs of punches 26 adjustable thereon; die plates 34 corresponding thereto, 70 supported in suitable bases; a driven shaft 6 in the machine; eccentrics on said shaft with connecting rods or pitmen connected to the said punch-heads to actuate the same simultaneously; shears 30 secured to said 75 punch-heads for cutting off the punched strips; a patter plate 41 below each of said shears; reciprocating pins for supporting the same; feed rolls 16—17, 16—17 for delivering the strips of strawboard to the punch and shears; a cam wheel on the lower feed roll shaft of each pair to actuate the corresponding patter; suitable guides for guiding the said strips to said feed rolls; ratchet mechanism; suitable disks 11 and 11 on the 80 feed roll shafts for carrying said ratchet mechanisms; a rod 12, for coupling said disks for actuating the said feed rolls by a step-by-step movement; a pitman 9, a disk on the end of the shaft having a wrist-pin 8 85 to which said pitman is coupled, for actuating the ratchets of the feed rolls; an endless carrier 84, consisting of a pair or sprocket chains oppositely-arranged sprocket-wheels 65 and 65 within the said frame-wor'k to support 90 said carrier; a lower shaft 48 and an upper shaft 66 to support said sprocket - wheels; adjustable journal bearings for said upper shaft 66 to put tension on the said carrier; 95 suitable cross-arms 72 at intervals on the 100 said carrier 84; guides 76 for the ends of said cross-arms at each side of said punches to keep them in their proper relation to the said punching machines; plates or forms 77; suitable rock shafts 73 for carrying said plates or forms one of which is journaled in each of said cross-bars 72; rows of oppositely-faced jaws on the face of each of said plates, the jaws being movable in relation to each other; means for opening the jaws to 105 receive the cut off strips as the plates are passing the first punch-head; means for opening each of the jaws on the plate after the same have passed both punch-heads, to permit the withdrawal of the completed egg case 110 filler; fingers 74—75 at right angles to each other on the inner end of the roc' shaft 73, at different points on the length thereof; guides 85 extending from near the bottom around the frame parallel to the path of the 115 carrier, past the upper punch and positioned to engage the fingers 74 of each of said plates or forms as it passes; guides 86 positioned within the guide 85 and between the opposite ends thereof to embrace the finger 75 to 120 turn the table or form at right angles to its initial position as it passes the lower punch and cutter and permit the same to be released and swung back to the initial position as it passes from said guides; a feed mech- 125 .

anism for the carrier consisting of the ratchet wheels and pawls on opposite ends of the shaft 48, an eccentric 50 on the shaft 48 with connections 51 for actuating one of the said 5 ratchets to secure the shorter steps, and a cam 55 toward the opposite end of said shaft 48, with connections for actuating the pawl of the opposite ratchet a double stroke, the notches of the ratchet on the 10 double stroke pawl being separated so that the same operates only at widely separated intervals, as the shaft is rotated or driven by the shorter strokes of the first-named ratchet, all coacting for the purpose specified.

15 12. In an egg crate filler machine, the combination of a suitable frame 1; a pair of punch-heads 20—20 arranged one above the other carrying gangs of punches 26 adjustable thereon; die plates 34 corresponding thereto, 20 supported in suitable bases; means for actuating said punch heads simultaneously; shears carried by the said punch heads for cutting off the punched strips; means for delivering the same into suitable supports; an 25 endless carrier 84, consisting of a pair of sprocket chains oppositely-arranged sprocket-wheels 65 and 65 within the said frame-work to support said carrier; a lower shaft 48 and an upper shaft 66 to support said sprocket-wheels; adjustable journal bearings for said 30 upper shaft 66 to put tension on the said carrier; suitable cross-arms 72 at intervals on the said carrier 84; guides 76 for the ends of said cross-arms at each side of said punches 35 to keep them in their proper relation to the said punching machines; plates or forms 77; suitable rock shafts 73 for carrying said plates or forms; one of which is journaled in each of said cross-bars 72; rows of oppositely-faced 40 jaws on the face of each of said plates, the jaws being movable in relation to each other; means for opening the jaws to receive the cut off strips as the plates are passing the first punch-head; means for opening each of the 45 jaws on a plate after the same have passed both punch-heads to permit the withdrawal of the completed egg case filler; fingers 74—75 at right angles to each other on the inner end of the rock shaft 73, at different points on 50 the length thereof; guides 85 extending from near the bottom around the frame parallel to the path of the carrier, past the upper punch and positioned to engage the fingers 74 of each of said plates or forms as it passes; 55 guides 86 positioned within the guide 85 and between the opposite ends thereof to embrace the finger 75 to turn the table or form at right angles to its initial position as it passes the lower punch and cutter and permit the same to be released and swung back to the initial position as it passes from said guides; a feed mechanism for the carrier consisting of the ratchet wheels and pawls on opposite ends of the shaft 48, an eccentric 50 60 on the shaft 48, with connections 51 for ac-

tuating one of the said ratchets to secure the shorter steps, and a cam 55 toward the opposite end of said shaft 48, with connections for actuating the pawl of the opposite ratchet; a double stroke, the notches of the ratchet on the double stroke pawl being separated so that the same operates only at widely separated intervals, as the shaft is rotated or driven by the shorter strokes of the first-named ratchet, all coacting for the purpose specified.

13. In an egg crate filler machine, the combination of a suitable frame 1; a pair of punch-heads 20—20 arranged one above the other carrying gangs of punches 26 adjustable thereon; die plates 34 corresponding thereto, supported in suitable bases; a driven shaft 6 in the machine; eccentrics on said shaft with connecting rods or pitmen connected to the said punch-heads to actuate the same simultaneously; shears 30 secured to said punch-heads for cutting off the punched strips; a patter plate 41 below each of said shears; reciprocating pins for supporting the same; feed rolls 16—17, 16—17, for delivering the strips of strawboard to the punch and shears; a cam wheel on the lower feed roll shaft of each pair to actuate the corresponding patter; suitable guides for guiding the said strips to said feed rolls; ratchet mechanisms; suitable disks 11 and 11, on the feed roll shafts for carrying said ratchet mechanisms; a rod 12 for coupling said disks; for actuating the said feed rolls by a step-by-step movement; a pitman 9; a disk on the end of the shaft 6 having a wrist-pin 8 to which said pitman is coupled for actuating the ratchets of the feed rolls; an endless carrier 84, consisting of a pair of sprocket chains oppositely-arranged sprocket-wheels 65 and 65 within the said frame-work to support said carrier; a lower shaft 48 and an upper shaft 66 to support said sprocket-wheels; adjustable journal bearings for said upper shaft 66 to put tension on the said carrier; suitable cross-arms 72 at intervals on the said carrier 84; guides 76 for the ends of said cross-arms at each side of said punches to keep them in their proper relation to the said punching machines; plates or forms 77; suitable rock shafts 73 for carrying said plates or forms; one of which is journaled in each of said cross-bars 72; the said forms being of such dimension as to swing without interfering with each other; rows of oppositely-faced jaws on the face of each of said plates, the jaws being movable in relation to each other; means for opening the jaws to receive the cut off strips as the plates are passing the first punch-head; means for opening each of the jaws on a plate after the same have passed both punch-heads, to permit the withdrawal of the completed egg case filler; fingers 74—75 at right angles to each other on the inner end of the rock shaft 73, at different points on the 130

- length thereof; guides 85 extending from near the bottom around the frame parallel to the path of the carrier, past the upper punch and positioned to engage the fingers 74 of each of 5 said plates or forms as it passes; guides 86 positioned within the guide 85 and between the opposite ends thereof to embrace the finger 75 to turn the table or form at right angles to its initial position as it passes the 10 lower punch and cutter and permit the same to be released and swung back to the initial position as it passes from said guides; a brake mechanism for retarding the movement of 15 said endless carrier; suitable feed mechanism for advancing the carrier step-by-step as each plate is passing the punch-heads; a mechanism for advancing the carrier an increased distance sufficient to carry the next 20 succeeding plate on the carrier into operative relation with the punch mechanism and to compensate for the difference in the distances between the successive plates and between the successive rows of grippers on the same 25 plate; all coacting for the purpose specified.
14. In an egg crate filler machine, the combination of a suitable frame 1; a pair of punch-heads 20—20 arranged one above the other carrying gangs of punches 26 adjustable thereon; die plates 34 corresponding thereto, supported in suitable bases; means for actuating said punch heads simultaneously; shears carried by the said punch-heads for cutting off the punched strips; means for 30 delivering the same into suitable supports; an endless carrier 84, consisting of a pair of sprocket chains oppositely-arranged sprocket wheels 65 and 65 within the said frame-work to support said carrier; a lower shaft 48 and an 35 upper shaft 66 to support said sprocket-wheels; adjustable journal bearings for said upper shaft 66 to put tension on the said carrier; suitable cross-arms 72 at intervals on the said carrier 84; guides 76 for the ends of said 40 cross-arms at each side of said punches to keep them in their proper relation to the said punching machines; plates or forms 77; suitable rock shafts 73 for carrying said plates or forms; one of which is journaled in each of 45 said cross-bars 72; the said forms being of such dimension as to swing without interfering with each other; rows of oppositely-faced jaws on the face of each of said plates, the jaws being movable in relation to each other; 50 means for opening the jaws to receive the cut off strips as the plates are passing the first punch-head; means for opening each of the jaws on a plate after the same have passed both punch-heads to permit the withdrawal 55 of the completed egg case filler; fingers 74—75 at right angles to each other on the inner end of the rock shaft 73; at different points on the length thereof; guides 85 extending from near the bottom around the frame parallel 60 to the path of the carrier, past the upper 65 plate and positioned to engage the fingers 74 of each of said plates or forms as it passes; guides 86 positioned within the guide 85 and between the opposite ends thereof to embrace the finger 75 to turn the table or form at right angles to its initial position as it passes the lower punch and cutter and permit the same to be released and swung back to the initial position as it passes from said guides; a brake mechanism for retarding the movement of 70 said endless carrier; suitable feed mechanism for advancing the carrier step by step as each plate is passing the punch-heads; a mechanism for advancing the carrier an increased distance sufficient to carry the next 75 succeeding plate on the carrier into operative relation with the punch mechanism and to compensate for the difference in the distances between the successive plates and between the successive rows of grippers on the same 80 plate; all coacting for the purpose specified.
15. In an egg crate filler machine, the combination of a suitable frame 1; a pair of punch-heads 20—20 arranged one above the other carrying gangs of punches 26 adjustable thereon; die plates 34 corresponding thereto, supported in suitable bases; a driven shaft 6 in the machine; eccentrics on said shaft with connecting rods or pitmen connected to said punch-heads to actuate the 90 same simultaneously; shears 30 secured to said punch-heads for cutting off the punched strips; a patter plate 41 below each of said shears; reciprocating pins for supporting the same; feed rolls 16—17, 16—17 for delivering the strips of strawboard to the punch and shears; a cam wheel on the lower feed roll shaft of each pair to actuate the corresponding patter; suitable guides for guiding the 95 said strips to said feed rolls; ratchet mechanisms; suitable disks 11 and 11, on the feed roll shafts for carrying said ratchet mechanisms; a rod 12 for coupling said disks for actuating the said feed rolls by a step-by-step movement; a pitman 9 a disk on the end of 100 the shaft 6 having a wrist-pin 8 to which said pitman is coupled for actuating the ratchets of the feed rolls; an endless carrier 84, consisting of a pair of sprocket chains oppositely-arranged sprocket-wheels 65 and 65 within 105 the said frame-work to support said carrier; a lower shaft 48 and an upper shaft 66 to support said sprocket wheels; adjustable journal bearings for said upper shaft 66 to put tension on the said carrier; suitable cross-arms 110 72 at intervals on the said carrier 84; guides 76 for the ends of said cross-arms at each side of said punches to keep them in their proper relation to the said punching machines; plates or forms 77; suitable rock shafts 73 for carrying said plates or forms one of which is journaled in each of said cross-bars 72; the said forms being of such dimension as to swing without interfering with each other; rows of oppositely-faced jaws on the face of 115 120 125 130

each of said plates, the jaws being movable in relation to each other; means for opening the jaws to receive the cut off strips as the plates are passing the first punch-head; 5 means for opening each of the jaws on a plate after the same have passed both punch-heads, to permit the withdrawal of the completed egg case filler; fingers 74-75 at right angles to each other on the inner end of the rock shaft 73, at different points on the length thereof; guides 85 extending from near the bottom around the frame parallel to the path of the carrier, past the upper punch and positioned to engage the fingers 74 of each of said plates or forms as it passes; guides 86 positioned within the 75 guide 85 and between the opposite ends thereof to embrace the finger 75 to turn the table or form at right angles to its initial position as it passes the lower punch and cutter and permit the same to be released and 80 swung back to the initial position as it passes from said guides; suitable feed mechanism for advancing the carrier step by step as each plate is passing the punch-heads; and a mechanism for advancing the carrier an increased distance sufficient to carry the next succeeding plate on the carrier into operative relation with the punch mechanism and to compensate for the difference in the distances between the successive plates and between the successive rows of grippers on the same plate; all coacting for the purpose specified.

17. In an egg crate filler machine, the combination of a suitable frame 1; a pair of punch-heads 20-20 arranged one above the other carrying gangs of punches 26; die plates 34 corresponding thereto, supported in suitable bases; a driven shaft 6 in the machine; eccentrics on said shaft with connecting rods or pitmen connected to the said punch-heads to actuate the same simultaneously; shears 30 secured to said punch-heads for cutting off the punched strips; a patter plate 41 below each of said shears; reciprocating pins for supporting the same; feed rolls 16-17, 16-17 for delivering the strips of strawboard to the punch and shears; a cam wheel on the lower feed roll shaft of each pair to actuate the corresponding patter; suitable guides for guiding the said strips to said feed rolls; ratchet mechanisms; suitable disks 11 and 11 on the feed roll shafts for carrying said ratchet mechanisms; a rod 12 for coupling said disks, for actuating the 105 said feed rolls by a step-by-step movement; a pitman 9; a disk on the end of the shaft 6 having a wrist-pin 8 to which said pitman is coupled, for actuating the ratchets of the feed rolls; an endless carrier arranged to 110 travel in front of said punch-heads; plates or forms carried by the said carrier, supported to swing on their vertical axes as they pass from the first punch-head to the second; suitable clamping means on the said plates 115 or forms to receive the strips in properly spaced position to form an egg case filler; and means for releasing the said clamps after

10 15 20 25 30 35 40 45 50 55 60 65 70 75 80 85 90 95 100 105 110 115 120 125

the filler is formed for discharging it from the machine, all coacting for the purpose specified.

18. In an egg crate filler machine, the combination of a suitable frame 1; a pair of punch-heads 20—20 arranged one above the other carrying gangs of punches 26; dieplates 34 corresponding thereto, supported in suitable bases; a driven shaft 6 in the machine; 10 eccentrics on said shaft with connecting rods or pitmen connected to the said punch-heads to actuate the same simultaneously; shears 30 secured to said punch-heads for cutting off the punched strips; a patter plate 41 below each of said shears; reciprocating pins for supporting the same; feed rolls 16—17, 16—17, 15 for delivering the strips of strawboard to the punch and shears; a cam wheel on the lower feed shaft of each pair to actuate the corresponding patter; suitable guides for guiding the said strips to said feed rolls; ratchet mechanisms; suitable disks 11 and 11 on the feed roll shafts for carrying said ratchet mechanisms; a rod 12 for coupling said disks, for actuating the said feed rolls by a step-by-step movement; a pitman 9; a disk on the end of the shaft 6 having a wrist-pin 8 to which said pitman is coupled, for actuating the ratchets of the feed rolls; an endless carrier 20 arranged to travel in front of said punch-heads; plates or forms carried by the said carrier, supported to swing on their vertical axes as they pass from the first punch-head to the second; and suitable clamping means 30 for receiving the strips in properly spaced position to form an egg case filler, all coacting for the purpose specified.

19. In an egg crate filler machine, the combination of a suitable frame 1; a pair of punch-heads 20—20 arranged one above the other carrying gangs of punches 26; dieplates 34 corresponding thereto, supported in suitable bases; a driven shaft 6 in the machine; 45 eccentrics on said shaft with connecting rods or pitmen connected to the said punch-heads to actuate the same simultaneously; shears 30 secured to said punch-heads for cutting off the punched strips; feed rolls 16—17, 16—17, 50 for delivering the strips of strawboard to the punch and shears; suitable guides for guiding the said strips to said feed-rolls; ratchet mechanisms; suitable disks 11 and 11 on the feed roll shafts for carrying said ratchet mechanisms; a rod 12 for coupling said disks, for actuating the 55 said feed rolls by a step-by-step movement; a pitman 9; a disk on the end of the shaft 6 having a wrist-pin 8 to which said pitman is coupled, for actuating the ratchets of the feed rolls; an endless carrier 50 arranged to travel in front of said punch-heads; plates or forms carried by the said carrier, supported to swing on their vertical axes as they pass from the first punch-head to the second; and suitable clamping means 60 for receiving the strips in properly spaced position to form an egg case filler, all coacting for the purpose specified.

on the said plates or forms to receive the strips in properly spaced position to form an egg case filler, all coacting for the purpose specified.

20. In an egg crate filler machine, the combination of a suitable frame 1; a pair of punch-heads 20—20 arranged one above the other carrying gangs of punches 26; dieplates 34 corresponding thereto, supported in suitable bases; a driven shaft 6 in the machine; 70 eccentrics on said shaft with connecting rods or pitmen connected to the said punch-heads to actuate the same simultaneously; shears 30 secured to said punch-heads for cutting off the punched strips; feed rolls 16—17, 16—17, 80 for delivering the strips of strawboard to the punch and shears; ratchet mechanisms; suitable disks 11 and 11 on the feed roll shafts for carrying said ratchet mechanisms; a rod 12 for coupling said disks, for actuating the said feed rolls by a step-by-step movement; a pitman 9; a disk on the end of the shaft 6 having a wrist-pin 8 to which said pitman is coupled, for actuating the ratchets of the feed rolls; an endless carrier 85 arranged to travel in front of said punch-heads; plates or forms carried by the said carrier, supported to swing on their vertical axes as they pass from the first punch-head to the second; and suitable clamping means on the said plates or forms 90 to receive the strips in properly spaced position to form an egg case filler, all coacting for the purpose specified.

21. In an egg crate filler machine, the combination of a suitable frame 1; a pair of punch-heads 20—20 arranged one above the other carrying gangs of punches 26; die plates 34 corresponding thereto, supported in suitable bases; a driven shaft 6 in the machine connections to said shaft to drive said punches simultaneously; shears 30 secured to said punch-heads for cutting off the punched strips; feed rolls 16—17, 16—17, 100 for delivering the strips of strawboard to the punch and shears; ratchet mechanisms; suitable disks 11 and 11 on the feed roll shafts for carrying said ratchet mechanisms; a rod 12 for coupling said disks, for actuating the said feed rolls by a step-by-step movement; a pitman 9; a disk on the end of the shaft 105 6 having a wrist-pin 8 to which said pitman is coupled, for actuating the ratchets of the feed rolls; an endless carrier arranged to travel in front of said punch-heads; plates or forms carried by the said carrier, supported to swing on their vertical axes as they pass from the first punch-head to the second; and suitable clamping means on the said plates or forms to receive the strips in properly spaced position to form an egg case filler, all 110 coacting for the purpose specified.

22. In an egg crate filler machine, the combination of a suitable frame 1; a pair of punch-heads 20—20 arranged one above the other carrying gangs of punches 26; die 115 130

plates 34 corresponding thereto supported in suitable bases; a drive shaft 6 in the machine; connections to said shaft to drive said punches simultaneously; shears 30 secured 5 to said punch-heads for cutting off the punched strips; feed rolls 16—17, 16—17, for delivering the strips of strawboard to the punch and shears; means for actuating the said feed rolls by a step-by-step movement; 10 an endless carrier arranged to travel in front of said punch-heads; plates or forms carried by the said carrier, supported to swing on their vertical axes as they pass from the first punch-head to the second; and suitable 15 clamping means on the said plates or forms to receive the strips in properly spaced position to form an egg case filler, all coacting for the purpose specified.

23. In an egg crate filler machine, the 20 combination of a suitable frame 1; a pair of punch-heads 20—20 arranged one above the other carrying gangs of punches 26; die plates 34 corresponding thereto, supported in suitable bases; a driven shaft 6 in the machine; connections to said shaft to drive said 25 punches simultaneously; shears 30 secured to said punch-heads for cutting off the punched strips; feed rolls 16—17, 16—17, for delivering the strips of strawboard to the punch and shears; means for actuating the 30 said feed rolls by a step-by-step movement; a carrier arranged to travel in front of said punch heads; plates or forms carried by the said carrier; and suitable clamping means on 35 the said plates or forms to receive the strips in properly spaced position to form an egg case filler, all coacting for the purpose specified.

24. In an egg crate filler machine, the 40 combination of a suitable frame; a double punching-head with shears arranged in proximity to each other; means for delivering strips of suitable material thereto; an endless carrier 84, consisting of a pair of sprocket 45 chains oppositely-arranged sprocket-wheels 65 and 65 within the said frame-work to support said carrier; a lower shaft 48 and an upper shaft 66 to support said sprocket wheels; adjustable journal bearings for said upper 50 shaft 66 to put tension on the said carrier; suitable cross arms 72 at intervals on the said carrier 84; guides 76 for the ends of said cross-arms at each side of said punches to keep them in their proper relation to the 55 said punching mechanism; plates or forms 77; suitable rock shafts 73 for carrying said plates or forms, one of which is journaled in each of said cross-bars 72; rows of oppositely-faced jaws 80 and 81 on the face of each of said plates, one set of jaws 81 being fixed and the other set of jaws 80 being movable; a rock 60 shaft 78 to which the said movable jaws 80 are secured; a spring 79 to hold the said jaws normally closed; a spring finger 82 on each of said rock shafts; trip fingers 83 for acting upon the said spring finger 82 to open the jaws; a trip bar 87 toward the rear of the 65 machine for opening all of the jaws on each plate or table in passing; means for turning the plates or forms as they pass from the first punch to the second, for retaining the same in a proper position to receive the cut off strips; and a feed mechanism to feed the said carrier intermittently step by step while the plates or forms are passing the punches and with an increased movement when the next succeeding plate is passed to the punch, and to compensate for the difference in distances between the successive plates and between the successive rows of grippers on the same plate, all coacting substantially as described and for the purpose specified.

25. In an egg case filler machine, the combination of a suitable frame; a double punching-head with shears arranged in proximity to each other; means for delivering strips of 85 suitable material thereto; an endless carrier 84 consisting of a pair of sprocket chains oppositely-arranged sprocket-wheels 65 and 65 within the said frame-work to support said carrier; a lower shaft 48 and an upper shaft 90 66 to support said sprocket-wheels; suitable cross-arms 72 at intervals on the said carrier 84; guides 76 for the ends of said cross-arms at each side of said punches to keep them in their proper relation to the said punching 95 mechanism; plates or forms 77; suitable rock shafts 73 for carrying said plates or forms, one of which is journaled in each of said cross-bars 72; the said forms being of such dimensions as to swing without interfering 100 with each other; rows of oppositely-faced jaws 80 and 81 on the face of each of said plates, one set of jaws 81 being fixed and the other set of jaws 80 being movable; a rock shaft 78 to which the said movable jaws 80 105 are secured; a spring 79 to hold the said jaws normally closed; a spring finger 82 on each of said rock shafts; trip fingers 83 for acting upon the said spring finger 82 to open the jaws; a trip bar 87 toward the rear of the 110 machine for opening all of the jaws on each plate or table in passing; means for turning the plates or forms as they pass from the first punch to the second, for retaining the same in a proper position to receive the cut off strips; and a feed mechanism to feed the said carrier intermittently step by step while the plates or forms are passing the punches and with an increased movement when the next 115 succeeding plate is passed to the punch, and to compensate for the difference in distances between the successive plates and between the successive rows of grippers on the same plate, all coacting substantially as described and for the purpose specified.

26. In an egg case filler machine, the combination of a suitable frame; a double punching-head with shears arranged in proximity to each other; means for delivering strips of suitable material thereto; an endless carrier 130

84, consisting of a pair of sprocket chains oppositely-arranged sprocket-wheels 65 and 65 within the said frame-work to support said carrier; a lower shaft 48 and an upper shaft 66 to support said sprocket wheels; suitable cross-arms 72 at intervals on the said carrier 84; guides 76 for the ends of said cross-arms at each side of said punches to keep them in their proper relation to the said punching mechanism; plates or forms 77; suitable rock shafts 73 for carrying said plates or forms, one of which is journaled in each of said cross-bars 72; the said forms being of such dimension as to swing without interfering 15 with each other; rows of oppositely-faced jaws on the face of each of said plates for receiving the cut and punched strips of an egg case filler in properly spaced and crossed relation; means for turning the plates or 20 forms as they pass from the first punch to the second for retaining the same in a proper position to receive the cut off strips; and a feed mechanism to feed the said carrier intermittently step by step while the plates or forms 25 are passing the punches and with an increased movement when the next succeeding plate is passed to the punch, and to compensate for the difference in distances between the successive plates and between the successive 30 rows of grippers on the same plate, all coacting substantially as described and for the purpose specified.

27. In an egg case filler machine, the combination of a suitable frame; a double punching-head with shears arranged in proximity to each other; means for delivering strips of suitable material thereto; an endless carrier 35 84 consisting of a pair of sprocket chains oppositely-arranged sprocket-wheels 65 and 65 within the said frame-work to support said carrier; a lower shaft 48 and an upper shaft 66 to support said sprocket wheels; plates or forms 77 carried by said carrier; rows of oppositely-faced jaws 80 and 81 on the face of each of said plates, one set of jaws 81, being fixed and the other set of jaws 80 being movable; a rock shaft 78 to which the said movable jaws 80 are secured; a spring 79 to hold the said jaws normally closed; a spring finger 82 on each of said rock shafts; trip fingers 83 for acting upon the said spring finger 82 to open the jaws; a trip bar 87 toward the rear of the machine for opening all of the jaws on each plate or table in passing; means for turning the plates or forms as they pass from the first punch to the second for retaining the same in a proper position to receive the cut off strips; and a feed mechanism to feed the said carrier intermittently step by step while the plates or forms 40 are passing the punches and with an increased movement when the next succeeding plate is passed to the punch, and to compensate for the difference in distances between the successive plates and between the successive 45 rows of grippers on the same plate, all coacting substantially as described and for the purpose specified.

29. In an egg case filler machine, the combination of a suitable frame; a double punching-head with shears arranged in proximity to each other; means for delivering strips of suitable material thereto; an endless carrier 50 84 consisting of a pair of sprocket-chains oppositely-arranged sprocket-wheels 65 and 65 within the said frame-work to support said carrier; a lower shaft 48 and an upper shaft 66 to support said sprocket wheels; plates or forms 77 carried by said carrier; rows of oppositely-faced jaws 80 and 81 on the face of each of said plates one set of jaws 81 being fixed and the other set of jaws 80 being movable; a rock shaft 78 to which the 55 said movable jaws 80 are secured; a spring 79 to hold the said jaws normally closed; means for turning the plates or forms as they pass from the first punch to the second, for retaining the same in a proper position to receive the cut off strips; and a feed mechanism to feed the said carrier intermittently step by step while the plates or forms are passing the punches and with an increased movement when the next succeeding plate is passed to the punch, and to compensate for the difference in distances 60 between the successive plates and between the successive 65 rows of grippers on the same plate, all coacting substantially as described and for the purpose specified.

tween the successive rows of grippers on the same plate, all coacting as described and for the purpose specified.

28. In an egg case filler machine, the combination of a suitable frame; a double punching-head with shears arranged in proximity to each other; means for delivering strips of suitable material thereto; an endless carrier 70 84, consisting of a pair of sprocket chains oppositely-arranged sprocket-wheels 65 and 65 within the said frame-work to support said carrier; a lower shaft 48 and an upper shaft 66 to support said sprocket wheels; plates or forms 77 carried by said carrier; rows of oppositely-faced jaws 80 and 81 on the face of each of said plates, one set of jaws 81 being 75 fixed and the other set of jaws 80 being movable; a rock shaft 78 to which the said movable jaws 80 are secured; a spring 79 to hold the said jaws normally closed; a spring finger 82 on each of said rock shafts; trip fingers 83 for acting upon the said spring finger 82 to open the jaws; means for turning the plates or forms as they pass from the first punch to the second, for retaining the same in a proper 80 position to receive the cut off strips; and a feed mechanism to feed the said carrier intermittently step by step while the plates or forms are passing the punches and with an increased movement when the next succeeding plate is passed to the punch, and to compensate for the difference in distances between the successive plates and between the successive 85 rows of grippers on the same plate, all coacting substantially as described and for the purpose specified.

29. In an egg case filler machine, the combination of a suitable frame; a double punching-head with shears arranged in proximity to each other; means for delivering strips of suitable material thereto; an endless carrier 90 105 84 consisting of a pair of sprocket-chains oppositely-arranged sprocket-wheels 65 and 65 within the said frame-work to support said carrier; a lower shaft 48 and an upper shaft 66 to support said sprocket wheels; plates or forms 77 carried by said carrier; rows of oppositely-faced jaws 80 and 81 on the face of each of said plates one set of jaws 81 being fixed and the other set of jaws 80 being movable; a rock shaft 78 to which the 110 said movable jaws 80 are secured; a spring 79 to hold the said jaws normally closed; means for turning the plates or forms as they pass from the first punch to the second, for retaining the same in a proper position to receive the cut off strips; and a feed mechanism to feed the said carrier intermittently step by step while the plates or forms are passing the punches and with an increased movement when the next succeeding plate is passed to the punch, and to compensate for the difference in distances 115 between the successive plates and between the successive 120 rows of grippers on the same plate, all coacting substantially as described and for the purpose specified.

the successive rows of grippers on the same plate, all coacting substantially as described and for the purpose specified.

30. In an egg case filler machine, the combination of a suitable frame; a double punching-head with shears arranged in proximity to each other; means for delivering strips of suitable material thereto; an endless carrier 84 consisting of a pair of sprocket chains 10 oppositely-arranged sprocket wheels 65 and 65 within the said frame-work to support said carrier; a lower shaft 48 and an upper shaft 66 to support said sprocket wheels; plates or forms 77 carried by said carrier; 15 rows of oppositely-faced jaws 80 and 81 on the face of each of said plates, one set of jaws being fixed and the other set of jaws 80 being movable; means for turning the plates or forms as they pass from the first 20 punch to the second, for retaining the same in a proper position to receive the cut off strips; and a feed mechanism to feed the said carrier intermittently step by step while the plates or forms are passing the 25 punches and with an increased movement when the next succeeding plate is passed to the punch, and to compensate for the difference in distances between the successive plates and between the successive rows 30 of grippers on the same plate, all coacting substantially as described and for the purpose specified.

31. In an egg crate filler machine, the combination of a suitable frame; a double 35 punching-head with one head arranged above the other, with shears arranged in proximity to each other; means for delivering strips of suitable material thereto; an endless carrier; plates or forms supported to swing on trans- 40 verse axes in the plane of their travel; rows of oppositely-faced jaws 81 and 80 on the face of each of said plates, one set of jaws 81 being fixed and the other set of jaws 80 being movable; a rock shaft 78 to which the 45 said movable jaws 80 are secured; a spring 79 to hold the said jaws normally closed; a spring finger 82 on each of said rock shafts; suitable trips for said fingers to open the jaws as required; means of turning each 50 plate at right angles as it passes from one punch-head to the next; and a feed mechanism to advance the same intermittently as required, all coacting for the purpose specified.

32. In an egg case filler machine, the combination of a suitable frame; a double punching-head with one head arranged above the other, with shears arranged in proximity to each other; means for delivering the strips of suitable material thereto; an endless carrier; plates or forms supported to swing on transverse axes in the plane of their travel; 60 rows of oppositely-faced jaws on said plates to receive the strips; means for turning each plate at right angles as it passes from one punch-head to the next; and a feed mech- 65

anism to advance the same intermittently as required, all coacting for the purpose specified.

33. In an egg case filler machine, the combination of a suitable frame; a double punching-head with shears arranged in proximity to each other; means for delivering strips of suitable material thereto; an endless carrier; plates or forms supported to swing on transverse axes in the plane of their travel; 70 rock shafts for supporting said plates or forms; rows of oppositely-faced jaws on the face of each of said plates to receive the punched strips; fingers 74 and 75 at right angles to each other on the inner end of the 75 rock shaft at different points on the length thereof; guides 85 from near the bottom around the frame parallel to the path of the carrier, past the upper punch and positioned to engage the fingers 74 of each of said plates 80 or forms as it passes; guides 86 positioned within the guide 85 and between the opposite ends thereof to embrace the finger 75 to turn the plate or form at right angles to its initial position as it passes the lower punch 90 and cutter and permit the same to be released and swung back to the initial position as it passes from said guides; a feed mechanism for the carrier consisting of the ratchet wheels and pawls on opposite ends of the 95 shaft 48; an eccentric 50 on the shaft 48 with connections 51 for actuating one of said ratchets to secure the shorter steps; and a cam 55 toward the opposite end of said shaft 4 with connections for actuating the pawl of 100 the opposite ratchet; a double stroke, the notches of the ratchet on the double stroke pawl being separated so that the same operates only at widely separated intervals, as the shaft is rotated or driven by the shorter 105 strokes of the first-named ratchet, all coacting for the purpose specified.

34. In an egg case filler machine, the combination of a suitable frame; a double punching-head with shears arranged in proximity to each other; means for delivering strips to suitable material thereto; an endless carrier; plates or forms supported to swing on transverse axes in the plane of their travel; 110 rock shafts for supporting said plates or forms; rows of oppositely-faced jaws on the face of each of said plates to receive the punched strips; fingers 74 and 75 at right angles to each other on the inner end of the rock shaft at different points on the length 115 thereof; guides 85 extending from near the bottom around the frame parallel to the path of the carrier, past the upper punch and positioned to engage the fingers 74 of each of said plates or forms as it passes; guides 86 positioned within the guide 85 and between the opposite ends thereof to embrace the finger 75 to turn the plate or form at right angles to its initial position as it passes the lower punch and cutter and permit the same to be 120 125 130

released and swung back to the initial position as it passes from said guides; a feed mechanism for the carrier consisting of the ratchet wheels and pawls on opposite ends of the shaft 48; means for actuating one of the said ratchets to secure the shorter steps; and a cam 55 toward the opposite end of said shaft 48 with connections for actuating the pawl of the opposite ratchet; a double stroke, 5 the notches of the ratchet on the double stroke pawl being separated so that the same operates only at widely separated intervals, as the shaft is rotated or driven by the shorter strokes of the first-named ratchet, all coacting for the purpose specified.

35. In an egg case filler machine, the combination of a suitable frame; a double punching-head with shears arranged in proximity to each other; means for delivering strips of 20 suitable material thereto; an endless carrier; plates or forms supported to swing on transverse axes in the plane of their travel; rock shafts for supporting said plates or forms; rows of oppositely faced jaws on the face of 25 each of said plates to receive the punched strips; fingers 74 and 75 at right angles to each other on the inner end of the rock shaft at different points on the length thereof; guides 85 extending from near the bottom 30 around the frame parallel to the path of the carrier, past the upper punch and positioned to engage the finger 74 of each of said plates or forms as it passes; guides 86 positioned within the guide 85 and between the opposite 35 ends thereof to embrace the finger 75 to turn the plate or form at right angles to its initial position as it passes the lower punch and cutter and permit the same to be released and swung back to the initial position 40 as it passes from said guides; a feed mechanism for the carrier consisting of the ratchet wheels and pawls on opposite ends of the shaft 48; an eccentric 55 toward the opposite end of said shaft 48 with connections 51 for 45 actuating one of the said ratchets to secure the shorter steps; and means toward the opposite end of said shaft 48 with connections for actuating the pawl of the oppositeratchet; a double stroke, the notches of the ratchet 50 on the double stroke pawl being separated so that the same operates only at widely separated intervals, as the shaft is rotated or driven by the shorter strokes of the first-named ratchet, all coacting for the purpose specified.

36. In an egg case filler machine, the combination of a suitable frame; a double punching-head with shears arranged in proximity to each other; means for delivering strips of 60 suitable material thereto; an endless carrier; plates or forms to swing on transverse axes in the plane of their travel; rows of oppositely-faced jaws on the face of each of said plates to receive the punched strips; a feed mechan-

ism for the carrier consisting of the ratchet 65 wheels and pawls on opposite ends of the shaft 48; means for actuating one of the said ratchets to secure the shorter steps, and a cam 55 toward the opposite end of said shaft 70 48 with connections for actuating the pawl of the opposite ratchet; a double stroke, the notches of the ratchet on the double stroke pawl being separated so that the same operates only at widely separated intervals, as the shaft is rotated or driven by the shorter 75 strokes of the first-named ratchet, all coacting for the purpose specified.

37. In an egg case filler machine, the combination of a suitable frame; a double punching-head with shears arranged in proximity 80 to each other; means for delivering strips of suitable material thereto; an endless carrier; plates or forms supported to swing on transverse axes in the plane of their travel; rows of oppositely-faced jaws on the face of each 85 of said plates to receive the punched strips; a feed mechanism for the carrier consisting of the ratchet wheels and pawls on opposite ends of the shaft 48, an eccentric 50 on the shaft 48 with connections 51 for actuating 90 one of the said ratchets to secure the shorter steps, and means toward the opposite end of said shaft 48 with connections for actuating the pawl of the opposite ratchet; a double 95 stroke, the notches of the ratchet on the double stroke pawl being separated so that the same operates only at widely separated intervals, as the shaft is rotated or driven by the shorter strokes of the first-named ratchet, all coacting for the purpose specified. 100

38. In an egg case filler machine, the combination of a suitable frame; a double punching-head with one head arranged above the other, with shears arranged in proximity to each other; means for delivering strips of 105 suitable material thereto; an endless carrier; plates or forms supported to swing on transverse axes in the plane of their travel; rows of oppositely-faced jaws on the face of each of said plates, the jaws being movable in relation to each other; means for opening the jaws to receive the cut off strips as the plates are passing the first punch-head; means of opening all of the jaws on a plate after the same have passed both punch-heads, to permit the withdrawal of the completed egg case filler; means of turning each plate at right angles as it passes from one punch-head to the next; and a feed mechanism to advance the same intermittently as required, all coacting for the purpose specified. 110 115

In witness whereof, I have hereunto set my hand and seal in the presence of two witnesses.

LUCAS J. SMITH. [L. S.]
